UNITED STATES PATENT OFFICE.

JAMES A. JOHNSON, OF NORFOLK, VIRGINIA.

BOTTLE-WASHING MACHINE.

1,210,484.

Specification of Letters Patent. Patented Jan. 2, 1917.

Application filed November 8, 1915. Serial No. 60,430

To all whom it may concern:

Be it known that I, JAMES A. JOHNSON, a citizen of the United States, residing at Norfolk, in the county of Norfolk and State of Virginia, have invented certain new and useful Improvements in Bottle-Washing Machines, of which the following is a specification, reference being had to the accompanying drawings.

10 This invention relates to washing machines, and particularly machines designed for washing bottles.

The general object of the invention is the provision of a machine by which bottles as they are carried along a predetermined path may be washed, without, however, necessitating the stoppage of the bottles during the operation so that the bottles may travel continuously while the interior of the bottles is being cleaned.

Another object of the invention is to provide a machine which is entirely automatic in its action and which necessitates practically the services of but one man to place 25 the bottles in the supporting cups, the machine being so arranged that the bottles may be carried as they are washed to any suitable place and may be removed by the person who has charge of the filling machine. Thus 30 the machine is very economical of labor and is economical of time inasmuch as the bottles are washed in successive order and without any delay in their movement to the filling machine.

35 A further object of the invention is the provision of means whereby bottles may be successively moved by a carrier along a predetermined path and whereby a series of brushes may be inserted within a predetermined number of bottles and travel with the bottles through a predetermined distance during which the cleaning operation is performed.

40 A further object of the invention is the provision of means whereby as the bottles travel along a path of movement, brushes will be forced upward into the bottles, rotate therein, and travel with the bottles for a predetermined distance, mechanism then being provided for withdrawing the brushes and means also being provided whereby water may be forced into the bottles at the time the brushes are operated.

45 Another object of the invention is the provision of means for holding the bottles down

in position at the time the brushes are operating therein.

Other objects will appear in the course of the following description.

50 My invention is illustrated in the accompanying drawings, wherein:

Figure 1 is an elevation, partly in section, of my improved washing machine; Fig. 2 is an end elevation of the machine shown in Fig. 1; Fig. 3 is a perspective view of the brush carriage with the brush shafts; Fig. 4 is a longitudinal sectional view through the brush carriage; Fig. 5 is a fragmentary sectional view through the brush carriage, showing in section the gear for rotating the brush shaft and showing in section the water reservoir which forms part of the body of the carriage; Fig. 6 is a fragmentary vertical section of the bottle carrier, the cup for supporting the bottle, and one of the brush shafts; Fig. 7 is a sectional view on the line 7-7 of Fig. 6; Fig. 8 is a sectional view on the line 8-8 of Fig. 5; Fig. 9 is a fragmentary top plan view of the carriage shown in Fig. 3, the top plate being removed and the rods for shifting the carriage longitudinally being shown in section; Fig. 10 is a fragmentary view showing one of the yokes and the corresponding rod whereby the carriage is shifted longitudinally; Fig. 11 is a diagrammatic elevation showing in dotted lines various positions taken by the driving gears; Fig. 12 is a fragmentary side elevation showing the means for returning the carriage to its initial position; Fig. 13 is a fragmentary vertical section through the carriage and the lateral frame of the machine, also through the bottle supporting carrier; Fig. 14 is a vertical section on the line 14-14 of Fig. 1.

Generally speaking, it may be said that I provide an endless carrier having thereon a series of bottle receiving cups which travel in a closed path. In order to provide for the support of the endless carrier and for the washing mechanism, I provide a frame comprising the vertical members 2 and the horizontally disposed members 3. The horizontally disposed members 3 are arranged in spaced relation and disposed opposite each other as illustrated clearly in Fig. 2, and the carrier 4 moves between these horizontal members during its upper flight. To this end the horizontal members 3 support by means of suitable brackets and bearings transverse

shafts 5 and 6 whereon are mounted the pairs of supporting sprocket wheels 7 and 8, respectively, with intermediate idler sprocket wheels 9. Toward the base of the machine there are provided the longitudinally extending members 10 upon which are mounted the pairs of sprocket wheels 11 and 12. In Fig. 1 I have shown completely only one end of the endless carrier 4, but have indicated in this figure sprocket wheels 13 over which the other end of the endless carrier is adapted to pass and may be supported. The endless carrier 4 at its upper flight passes over the sprocket wheels 7, 8 and 13, then passes downward from the sprocket wheels 13 to the sprocket wheels 11 and extends along its lower flight from the sprocket wheels 11 to the sprocket wheels 12. Preferably one of the sprocket wheels, as for instance the sprocket wheel 11, is mounted upon shiftable brackets or bearings so that the belt may be tightened up, the brackets or bearings being shifted by means of adjusting screws 14.

As shown in Fig. 2 and Figs. 13 and 14, there is one pair of sprocket chains 4 forming the endless carrier, these chains being composed of links pivoted to each other in the usual manner and the chains being connected by means of cross braces in the manner illustrated in Fig. 7. These cross braces or connections each consist of a plate 15 which is riveted or otherwise attached at its ends to the links of the endless carrier.

Mounted upon this plate 15 is a bottle receiving cup 16 having a downwardly extending neck 17 adapted to receive the neck of a bottle. This neck at its lower end is annularly flanged and bolted, riveted or otherwise attached to the plate 15. Disposed within the neck 17 is an annular collar 18 upon which the lower end of the bottle A is adapted to rest, this collar being held in place by a set screw 19 or in any other convenient manner. The bore of the member 18 has approximately the same diameter as the interior diameter of the bottle neck. The bottle cups or holders are arranged in spaced relation upon the endless carrier and are adapted to support the bottles A in an inverted position, as illustrated clearly in Figs. 1 to 6. The sprocket wheels 8 are mounted upon the shaft 6 which is operatively connected to the driving shaft of the machine as will now be stated. The driving shaft of the machine is designated 20, this driving shaft being mounted in suitable bearings upon the vertical members 2. This driving shaft carries upon it the sprocket wheel 21 over which passes a sprocket chain 22 which engages with a relatively large sprocket wheel 23 mounted upon the shaft 6. The lower flight of the sprocket chain 22 passes over an idler sprocket wheel 24 mounted in any suitable

manner but so arranged, as illustrated in Fig. 1, as to keep the lower flight of the sprocket chain taut.

As before stated, I provide a plurality of brushes which are vertically shiftable so as to carry them into or out of the bottles to be cleaned, and I also provide means whereby these brushes may be shifted longitudinally with the movement of the bottles so that the brushes will travel with the bottles a predetermined distance during the washing process. To this end I provide longitudinally extending laterally disposed tracks 25 which at their ends are upwardly bent and attached to the rails or longitudinal members 3. Slidably mounted upon these rails 25 is the brush carriage designated generally 26 and which is illustrated in Fig. 3. This brush carriage is formed in two sections, 27 and 28, the inner faces of the sections being recessed to form a gear chamber 29. The ends of this carriage 29 are laterally enlarged as at 30, and this lateral enlargement is longitudinally slotted as at 31. The two sections 27 and 28 are held in engagement with each other by lateral flanges 32 through which bolts pass. The grooves 31 in the lateral extensions 30 are adapted to engage with the rails 25, these rails on their inner edges abutting against the edges 95 of the flanges 32. By this means the carriage is held from all lateral movement but may be longitudinally shifted upon the rails 25.

Disposed within the gear chamber 29 are a plurality of gear wheels 33 shown as four in number, though the number of these gear wheels is immaterial. These gear wheels mesh with each other so as to form a train of gears and each gear wheel is formed with an upwardly extending annular sleeve 34 which extends out through the top section 27 of the carriage. Each gear is formed at its center with a many-sided bore 35 through which the corresponding brush shaft 36 passes. This brush shaft 36 has a portion of its length many-sided to conform to the shape of the bore 35 and each shaft is hollow. At its lower end each shaft is mounted in a stepped bearing 37 and the lower end of each shaft communicates with an opening 38 formed in a water reservoir or tank 39 which is movable vertically, this member 39 thus forming not only a water chamber or tank but also a support for the lower ends of the several shafts 36 as illustrated most clearly in Fig. 1. The several gears 33 are actuated by providing one of the gears with a downwardly extending sleeve 40 which carries at its lower end the beveled gear wheel 41 which meshes with a beveled gear wheel 42 mounted upon a transversely extending shaft 43. This shaft 43 is mounted in a bracket 44 which depends from and is attached to the under side of the carriage 26 as illustrated

most clearly in Fig. 2. Mounted upon the shaft 43 is a gear wheel 45 and depending from the shaft 43 and swingingly mounted thereon on opposite sides of the gear wheel 45 are the links 46. These links support a shaft 47 upon which is mounted a gear wheel 48. This gear wheel 48 meshes with a gear wheel 49 mounted upon a shaft 50 and supported in suitable bearings upon the members 2^a. Links 51 are disposed on each side of the gear wheel 48 and engaging with the shaft 47 and with the shaft 50. This shaft 50 on the opposite side of the machine carries upon it a gear wheel 52 which in turn meshes with the driving gear wheel 53 mounted upon the driving shaft 20 which is driven in any suitable manner as by means of a belt 54 passing over a suitable belt wheel. It is this shaft 20 which carries upon it the sprocket wheel 21 whereby the bottle carrier is driven, as before described. The water chamber or reservoir 39 which carries the lower ends of the brush spindles or shafts 36 is intended to have vertical movement so as to carry the brushes upward into the bottles and downward and out of the bottles. To this end I mount upon a pair of supports 2 the crank shaft 55 having the crank 56. Pivotaly connected to the reservoir or container 39 is a link 57 whose free end is slotted as at 58, the crank pin of the crank shaft 56 engaging this slot. It will now be seen that as the shaft 55 is rotated the water reservoir and brush spindle support 39 will be vertically reciprocated. In order to rotate the shaft 55 I mount upon it the sprocket wheel 59 having teeth which engage with the downwardly extending flight of the belt 22 as shown clearly in Fig. 1. I do not wish, however, to be limited to this means of operating this shaft. It is for the purpose of causing the belt to engage the sprocket wheel 59 that I provide the idler sprocket wheel 24 which lifts the lower flight of the belt into engagement with the sprocket wheel 59.

For the purpose of causing the carriage 26 and the water container 39 to shift longitudinally and travel with the bottle conveyor or carrier for a certain predetermined portion of the movement of the latter, I provide the water container 39 at its ends with certain vertically disposed rods or fingers which act as clutches for movement into engagement with the links of the conveyor or bottle carrier. To this end I mount upon the end of the water container 39 the cross bar 60, as shown clearly in Fig. 13, upon the ends of which are hingedly mounted the upwardly extending rods 61. These rods as shown clearly in Fig. 9 pass upward between pairs of rollers 62 mounted upon brackets 63, these brackets being mounted upon the ends of the carriage 26. The rods thus have vertical movement with relation

to the carriage 26 but any longitudinal movement of the rods will cause a longitudinal movement of the carriage. These rods 61 are normally out of engagement with the links of the carrier 4 but when the water container 39 rises the rods 61 will be carried upward and engage between the links of the carrier 4 and then the forward movement of the carrier 4 will be communicated to the water container 39 and also to the carriage 26 so that the water container, the carriage and brush spindles 36 will move along with the carrier 4 until the crank 56 commences to move downward whereupon the rods 61 will be shifted downward and eventually be shifted out of engagement with the links of the carrier. The water container 39 and the carriage 26 should then be shifted rearward to their initial positions, and to this end I have provided the mechanism illustrated in detail in Fig. 12 wherein a wheel 64 is shown as mounted upon the shaft 55 and as provided with the laterally projecting pin 65. Pivotaly mounted in any suitable manner is a lever 66 whose upper extremity is connected to the carriage 26. When this carriage has been moved the full distance with the belt 4 by the mechanism heretofore described, the lower end of this lever will be disposed in the path of movement of the pin 65 and at this period the pin 65 will be in the position illustrated in Fig. 12. The pin 65 will engage with the lower end of the lever 66 at the time when the crank 56 has shifted to such a position that the water container 39 will be lowered to an extent sufficient to withdraw the rods 61 from their engagement with the links of the endless carrier 4. When the pin 65 engages with the lever 66 it will shift the upper end of the lever rearward and return the carriage to its original position ready for a new operation.

I have illustrated in Fig. 1 four brush spindles 36 mounted upon the carriage 25 and have also illustrated two bottle washing pipes 67 and 68 also operatively supported upon the water container 39. These pipes 67 and 68 do not rotate. The pipe 67 extends downward and opens into the water container 39, while the tube 68 extends downward and is connected by an elbow 69 to the water container. The upper ends of these tubes, as illustrated in Figs. 13 and 14, are provided with roses or spraying nozzles 70 whereby water may be sprayed with force against the sides of the bottles to thoroughly rinse them. The brush spindles 36 are tubular, as before stated, and each carries at its upper end the brushes 71, the tubular spindle discharging water into the bottle by any suitable aperture. I do not wish to be limited to the exact manner in which the brush is connected to the tubular spindle.

For the purpose of keeping the water chamber or reservoir 39 filled with water and providing for forcing water up through the brushes and spray nozzles 70, I connect 5 to the rear end of the water container 39 the flexible pipe 72 which at its other end is operatively connected to a supply pipe 73. Adjacent the supply pipe 73 the flexible pipe 72 is provided with a valve 74 whose 10 spindle has a radial arm 75 provided with a pin 76 which engages in a slot 77 formed in a depending arm 78 carried upon the water container 39. This construction is such that when the water container 39 is lowered 15 the valve will be closed, but that when the water container is raised so as to carry the brushes into the bottles the valve will be opened. The slot 77 permits the valve to remain open or remain closed while the 20 brushes are moving.

In order to hold the bottles down while the brushes and spray tubes are moving upward into the bottles and operating therein, I mount upon the standards 79 the 25 pivoted plate 80 which when it is in a horizontal position rests upon the tops of the bottles A. To the free end of this plate 80 are connected one or more links 81 which extend downward and at their 30 lower ends are operatively connected to the water container 39. Preferably the lower ends of the links are screw-threaded for engagement with adjusting nuts 82. It will thus be seen that when the water container 35 and the carriage move downward the plate 80 will be lifted, releasing the bottles, but when the carriage moves upward the plate 80 will be depressed against the tops of the bottles holding them in place.

40 The specific operation of the gears whereby the brush spindles are rotated is obvious from Fig. 11. These gears are so arranged as to permit of a longitudinal movement of the carriage upon which the 45 brush spindles are mounted and also permit of a vertical movement of the carriage and of the water container. This is accomplished by linking the gear wheels 45 and 49 to the relatively large gear wheel 48 so 50 that as the carriage moves up or as it moves longitudinally the links will shift to permit the large gear wheel 48 to be raised or lowered and permit the gears 45 and 49 to shift away from or toward each other 55 while remaining in driving engagement.

The general operation of my mechanism is as follows: The carrier with the bottle supporting cups thereon is constantly moving and the bottles are placed in the cups 60 as the cups arrive at the upper flight of the carrier. When the cups have arrived at a predetermined position the water container rises and the rods 61 engage the links of the carrier. At the same moment the 65 spindles rise and are forced through the

70 cups into the bottles. The brush spindles are constantly rotated by means of the gears contained within the gear chamber 29 and the brushes thoroughly scrub the interior of the bottle. Water is forced into the bottles during this period by the mechanism illustrated. The last two bottles which have been previously scrubbed are engaged by the spray tubes and thus the bottles are 75 thoroughly rinsed. When the bottles are entirely cleansed the brushes and the spray tubes are withdrawn and then inserted in a new set of bottles in an obvious manner. The bottles are eventually moved from the carrier to any suitable place. It will be 80 understood that the carrier may be of any desired length so as to carry the bottles to any desired position in the factory.

The principal advantages of my invention reside in the fact that it is automatic 85 in its action, that it is extremely simple and requires the attention of but one operator who places the bottles upon the carrier. Furthermore, the bottles are thoroughly scrubbed on the inside and thoroughly washed and rinsed before passing 90 onward to the filling machine.

While I have illustrated what I have found to be a most practical embodiment 95 of my invention, I wish it understood that various changes might be made in the details of construction and arrangement of parts without in any way departing from the spirit of the invention.

Having thus described this invention, what 100 is claimed is:—

1. In a machine of the character described, an endless carrier, a supporting member having movement parallel to the carrier and at right angles to its path of movement, operating implements carried upon the supporting member, means for shifting the supporting member toward or from the carrier, and means on the supporting member engageable with the carrier upon a movement of the supporting member 110 toward the carrier and disengageable therefrom upon a reverse movement whereby to cause a longitudinal movement of the supporting member with the carrier for a 115 predetermined distance.

2. An endless carrier including spaced links, a supporting member movable parallel to the carrier and toward and from the carrier, operating implements mounted 120 thereon, and means in connection with the supporting member and movable therewith engageable with the links of the carrier upon a movement of the supporting member toward the carrier and disengageable therefrom upon a reverse movement whereby to cause a common longitudinal movement of the carrier and supporting member for a 125 predetermined distance.

3. In a bottle cleaning machine, a bottle 130

carrier movable in a closed path and having means thereon for supporting bottles, a carriage movable parallel to the carrier, a bottle cleaning member mounted upon the carriage for movement transverse to the movement of the carrier, and means for engaging the carriage with the carrier for common movement, then projecting the bottle cleaning member into the bottle, then 10 retracting the bottle cleaning member and successively disengaging the carriage from the carrier and then shifting the carriage back to its initial position.

4. In a bottle cleaning machine, a bottle carrier movable in a closed path and having means thereon for supporting bottles, a carriage movable parallel to the carrier, a bottle cleaning member mounted upon the carriage for movement transverse to the movement of the carrier, means for engaging the carriage with the carrier for common movement, then projecting the bottle cleaning member into the bottle, then retracting the bottle cleaning member and successively disengaging the carriage from the carrier and then shifting the carriage back to its initial position, and means for rotating the bottle cleaning member.

5. In a bottle washing machine, a bottle carrier movable in a closed path and having means thereon for supporting bottles in an inverted position, a carriage movable beneath the carrier and parallel thereto, a rotatable cleaning member mounted upon the carriage, means for giving constant rotation to said cleaning member, means for engaging the carriage with the carrier for common movement and successively projecting the cleaning member upward into the bottles supported upon the carrier, means for ejecting water from the cleaning member, while it is in its projected position, and means for retracting said cleaning member from the bottle and successively disengaging the carriage from the carrier and returning the carriage to its initial position.

6. In a bottle washing machine, a bottle carrier movable in a closed path and having means thereon for supporting bottles in an inverted position, said means including cup-shaped members, a carriage disposed beneath the carrier and movable in a path parallel to the carrier, a water container operatively supported beneath the carrier for vertical movement, rotatable brush spindles mounted upon the water container, means for causing constant rotation to said spindles, means for vertically reciprocating the water container and means carried by said container and reciprocatable therewith for simultaneously engaging or disengaging the carriage and the water container with the carrier, means operating while the water container is raised for ejecting water from the water container into and through the

brush spindles, and means acting when the water container and carriage are lowered and disengaged from the carrier to shift the carriage and water container to their initial positions.

7. In a bottle washing machine, an endless bottle carrier, a vertically and longitudinally movable implement support disposed beneath the carrier, bottle washing implements mounted thereon, means for reciprocating said support toward and from the carrier, and means mounted on said support engageable with the carrier upon a movement of the support toward the carrier and disengageable therefrom upon a reverse movement to thereby cause a common longitudinal movement of the implement support and the carrier.

8. In a bottle washing machine, a bottle carrier movable in a closed path and having means thereon for supporting bottles in an inverted position, a carriage mounted beneath the carrier for longitudinal movement, a plurality of tubular bottle cleaning members extending through the carriage, gearing mounted upon the carriage for rotating said bottle cleaning members, but permitting their vertical movement, a water container supported below the carriage for vertical movement with relation thereto, said water container supporting the lower ends of the bottle cleaning members, means for vertically reciprocating the water container, means carried upon the water container and the carriage and engaging with the carrier upon the upward movement of the water container to cause a common horizontal movement of the carrier and carriage, but disengageable from the carrier when the water container is lowered to the lower end of its stroke, means for automatically causing the retraction of the carriage and the water container to its initial position, when the carrier is disengaged from the carriage, and means controlled by the reciprocation of the water container for forcing water into the water container.

9. In a bottle washing machine, a bottle carrier movable in a closed path and comprising oppositely disposed flexible members, transverse braces and inverted cups mounted thereon, tracks extending below, but parallel to the carrier for a predetermined distance, a carriage movable upon said tracks, a plurality of tubular brush spindles extending through said carriage and movable vertically with relation thereto, gearing mounted in said carriage and engaging the brush spindles to rotate them, means for constantly rotating said gearing, a water container supported below the carriage, but vertically movable with relation thereto, into which said cup spindles open the container supporting the lower ends of the cup spindles, vertical rods carried upon

the end of the water container, and engaged with the carriage, said rods when the water container moves upward engaging with the links of the carrier, means for vertically reciprocating the water container to cause the engagement of the rods with the carrier and cause the vertical projection of the brush spindles, means operating to return the carriage and the water container to an initial position, upon a depression of the rods and brush spindles, a water supply pipe entering the container, a valve in the supply pipe, and means operating upon an elevation of the water container to open said valve and upon a depression of the water container to close the valve.

10. In a bottle washing machine, a bottle carrier movable in a closed path and having means thereon for supporting bottles in an inverted position, a water container movable longitudinally and vertically beneath the carrier, a plurality of brush spindles extending upward from the water container and adapted to be projected into or through the bottle supporting means, means for vertically reciprocating the water container, means for longitudinally shifting the water container with the carrier when the water container is raised, means for shifting the water container rearward opposite to the movement of the carrier when the water container is lowered, and means for rotating the spindles comprising a plurality of intermeshing gear wheels, in each one of which a spindle is mounted for vertical movement and common rotation, and means for driving said gear wheels including a shaft operatively engaging one of said gear wheels and having a gear wheel thereon, a driving shaft having a gear wheel thereon, and an intermediate gear wheel meshing with both of said last named gear wheels and supported by links pivotally connecting the shafts of the intermediate gear wheel and the two intermeshing gear wheels.

11. In a machine of the character described, an endless carrier, longitudinally extending carrier guides, a longitudinally extending guide parallel to the carrier guides, a supporting member operatively supported upon said last-named guide for longitudinal movement and movable toward and from the carrier, implements mounted upon said supporting member, and means mounted upon the supporting member and movable therewith engageable with the carrier upon a movement of the supporting member toward the carrier and disengageable therefrom upon a movement of the supporting member away from the carrier to thereby cause a common movement of the supporting member and carrier for a predetermined distance.

12. In a machine of the character described, an endless carrier, longitudinally

extending carrier guides, a longitudinally extending guide parallel to the carrier guides, a supporting member operatively supported upon said last-named guide, said supporting member being movable toward the carrier and longitudinally along the last-named guide, means for reciprocating said supporting member, means carried by the supporting member engageable with the carrier upon a movement of the supporting member toward the carrier and disengageable therefrom upon a reverse movement whereby to cause a movement of the supporting member with the carrier for a predetermined distance, and means for returning the supporting member to its initial position after it is disengaged from the carrier.

13. In a machine of the character described, an endless carrier, tracks supporting one flight of the carrier, longitudinally disposed guides parallel to the tracks, a member mounted upon said guides for longitudinal movement, a supporting member disposed beneath the first-named member and movable therewith, operating implements mounted upon the supporting member and passing loosely through the first-named member, means for reciprocating the supporting member toward and from the first-named member and the carrier, rods mounted upon said supporting member and reciprocatable therewith and engaging with the carrier upon a movement of the supporting member toward the carrier and disengaging therefrom upon a reverse movement to thereby cause a movement of the supporting member along said guide with and parallel to the carrier, and means for returning the supporting member and the member through which the said implements pass to their initial position upon a disengagement of the supporting member from the carrier.

14. In a bottle washing machine, an endless carrier having means for supporting bottles in an inverted position thereon, longitudinally disposed guides along which said carrier passes, a member movable toward and from the carrier, bottle washing implements carried by said member and movable into or out of operative engagement with the bottles upon a reciprocation of the member, and a hinged holder disposed above the carrier and operatively connected to the supporting member to close down upon the upper ends of the bottles as the supporting member rises and to shift away from the bottles as the supporting member is lowered.

15. In a bottle washing machine, an endless carrier, a track along which the carrier moves, means upon the carrier for supporting bottles in an inverted position, a member operatively supported to move parallel to the carrier and having standards extending above the carrier, an implement sup-

porting member coacting with the first-named member and vertically reciprocatable relative thereto, bottle cleaning implements having spindles mounted upon the supporting member and extending through the first-named member, means for reciprocating said supporting member and moving the first-named member and the supporting member longitudinally beneath the carrier in time therewith for a predetermined distance, a plate hinged upon said standards and adapted when lowered to bear against the upper

ends of the bottles mounted upon the carrier, and means mounted upon said supporting member for oscillating said plate to cause the plate to lower upon an upward movement of the supporting member and to rise upon a downward movement thereof.

In testimony whereof I hereunto affix my signature in the presence of two witnesses. 20
JAMES A. JOHNSON.
